UNITED STATES PATENT OFFICE

JOHANN ARTHUR MUELLER, OF BERLIN, GERMANY

STENCILING MACHINE

Application filed November 2, 1929, Serial No. 404,440, and in Germany July 13, 1929.

The invention relates to a demountable printing-drum with removable crank-pin for stenciling-machines, which:

1. Inks automatically without any mechanical arrangement or hindrance and without special trough or such like.

2. Takes the whole stock of ink inside the drum.

3. Diminishes the flow of ink towards the lower part of the printing-surface.

4. Provides a filling of ink without any loss and without soiling the hands.

5. Guides an automatic switch-weight-feeder rolling on ballbearings on horizontal rails with:

(a) Different printing-heights and
(b) Different lengths of the movement of the paper-feeder.

Fig. 1 shows the stencil-machine in a general view; Figs. 2, 2a the machine with demounted drum; Fig. 3 the drum with segment connected with a slotted swing-lever by means of an actuating arm moving the axle, on which the paper-feeder is attached, with regulation of the printing-height and length of the movement of the feeder; Fig. 3a, a front view showing the sheet feeding device; Fig. 4 the regulation of the pressure of the pressure-roller situated under the printing-drum; Fig. 4a shows the pressure roller throw-off; Figs. 5, 5a, 6, 7, 7a, the printing-drum with sieve and different arrangements for the printing-pad and stencil; Fig. 8 filling of ink through the side-plate of the drum by means of a tube; Figs. 9, 9a, 10, 10a, the automatic paper-feeder; Fig. 11 the automatic paper-feeder with automatic switch acting as soon as the last sheet of paper is consumed. Fig. 12 and Fig. 12a another arrangement for removing and fixing the crank pin, instead of a segment; Figs. 13 and 13a show the clamping means for one of the paper guides.

The printing-drum is a closed cylinder 1 Fig. 5 with filling-hole for ink 2 in the side-plate 3 of the drum 1 Figs. 5a, 8.

The circumference of the cylinder 1 is larger, than the surface of the paper, which has to be printed, Figs. 2, 5, 6, 7. The circumference of the cylinder 1 is partly pro-

vided with holes like a sieve, namely from 4 to 5, through which the ink passes from the inside of the drum 1 into the printing pad 6 Fig. 5. On top of this printing-pad is the stencil with writing, from which the prints are made.

In consideration of the fact that the ink, contained in the pad, is squeezed by the pressure-roller 11 Fig. 4, situated under the printing-drum, towards the sides, except the top-side, and especially towards the end of the stencil Fig. 5, the surface of the perforations is smaller on three sides (all except the top-side), than the surface to be printed and besides towards the end, about at point 7 Fig. 5 the surface is provided with less holes, notwithstanding the smaller surface.

The fewer holes have the purpose of giving less ink; this reduction can of course also be obtained by smaller holes. The arrangement of the perforations can be seen on the demounted drum 1 of Fig. 2.

Fig. 5 shows that a large part of the cylinder 1 from 4 to 5 downwards is not perforated being downwards as soon as the machine is out of use; this part takes the whole stock of ink and nothing can pass outside, when the machine is out of use.

When turning the drum 1, the ink flows along the inside of the drum 1 and ink is absorbed by the pad 6 Fig. 5 as much as consumed.

Having placed the holding means for the stencil and pad 8, 9 Fig. 5 on top of the cylinder 1 Fig. 5 a curve-plate 10 may be provided, in order to give a smooth rolling to the pressure-roller 11. Fig. 6 shows a slight alteration, namely hollows 12, 13 for the holding means 8, 9, over which the pressure-roller will roll. However, should the pressure-roller have a perfect smooth run, the hollows of Fig. 6 may be covered with small lids or the construction may be carried out as per Figs. 7, 7a.

The filling-up of the drum 1 with ink, in order to avoid any loss or soiling the hands, is arranged in such a manner, that the ink-package, for instance a tube 16 Fig. 8 fits properly into the filling-hole 2. The filling through the side-plate 3 of the drum 1 by

means of a tube Fig. 8 is preferable. The tap closing the filling-hole 2 is provided with a hole, that no vacuum may be formed inside the drum and that the temperature will 5 be the same inside as outside of the drum. Leaving off entirely the tap, for instance a ring with funnel 17 Fig. 8 has to be fixed inside around the filling-hole, if possible near to the axle of the drum, in order to avoid ink 10 dripping into the filling-hole and outside.

A removable crank pin in shape of a slotted segment 18 Figs. 2, 3 or a slotted crank 18a Figs. 12 and 12a or such like is fixed on the drum 1, which moves by means of an actuating arm 19 the swing-levers 20 putting in action the paper-feeder. By altering the crank-pin 12 the writing on the stencil on the drum becomes another position towards the feeder and the printing begins earlier or later, 20 which means, the print appears on the paper higher or lower.

The actuating arm 19 acts on a pair of slotted swing-levers 20, Fig. 3a, which are fixed and working together; by altering the position 25 of the actuating arm 19 at the swing-lever at point 21 Fig. 3 the length of the movement of the feeder becomes longer by moving upwards and narrower by moving downwards. By altering the length of the 30 actuating arm 19 at point 44 the feeder starts also earlier or later. The pair of swing-levers 20 moves an axle 23 Figs. 1, 2, 3, 3a running on ballbearings 24 on horizontal rails 22; in order to obtain a smooth run, it is advisable 35 to provide spiral springs, which pull the ball-bearings against the rails 22. On this axle 23 is attached the paper-feeder 25.

The known feeders for instance with ratchet and spring-finger are easily broken, 40 because the spring-finger works permanently against the ratchet. However, the feeders with horizontal slot and special brake have not only a long lost motion, but are also subject to breakage. The stoppage of the present 45 feeder is without any mechanical arrangements or cog-wheel or such like, but acts in that manner, that the axle of the feeder-roll 27, usually made of rubber, is moving freely in a slit, inclined to the paper, 26 Figs. 2, 9, 50 10; as soon as the feeder is out of action or moved forward, the roll 27 is leaning fast by the weight of the heavy feeder against the back 28a Figs. 9, 10, 10a, which is rough or provided with a file; however, drawing back 55 the feeder 25, the roll becomes free from the back and rolls in the slit without touching the back.

As soon as the last sheet of paper is consumed, the rubber-feeder-roll 27 would be 60 pressed against the table 28a and there is a likelihood, that the mechanism could be damaged. In order to avoid this, there is provided one (or two) legs 29 Figs. 9, 9a, 10, 11 on the axle 26 of the roll 27; this small leg 29 65 is shifting forwards and backwards on the

paper, but as soon as the last sheet of paper is consumed, the leg drops, the feeder being in the end-position, into the hollows 30 Figs. 9, 11 and raises automatically the feeder from the table 28 Fig. 11.

In order to have a central feeding, even, if the paper is not placed quite in the middle of the table 28a, the feeder can be moved sideways on the axle 23, in such a manner, that the feeder is always in the middle of the 75 paper.

Further there are a few more facilities:

The drum 1 is in slotted bearings 40 Figs. 1, 2, 3, which can be closed by bolts 41. Removing the bolts 41, the drum 1 can easily 80 be taken out, which is very advantageous for changing the colour of ink etc.

The paper-holders 32 are not fastened by screws, as it is the rule, but with eccentrics 33 Figs. 1, 2, 3 and 13, 13a. By turning the eccentric 33 to the left, the bracket 32 and the bolt with spring-ring 42 become free from the table 28; the paper-holding-bracket 32 can easily be shifted in the slit 43 Fig. 2, whereas turning the eccentric 33 to the right 90 the bracket 32 is pressed against the table 28 and the bracket 32 is instantly fixed.

The pressure-roller 11 can be regulated by means of a thumb-screw 34 from outside. Fig. 4 shows the drum 1, the pressure-roller 95 11 in a swing-bracket 35, generally known, which is pulled upwards by means of spring-spiral 36; the pressure is switched off by means of an eccentric 37 Figs. 1, 2, 4, 4a, also known. Up to the present the screws 100 for regulating the pressure-roller were uneasy to reach being generally underneath the machine and had to be operated by means of a key or screw-driver. The regulation is now done by hand from outside. The thumb-screw 34 Figs. 2, 4 is quite outside of the 105 machine.

As soon as the thumb-screw 34 is turned against the bracket 38 projecting from the frame of the machine, the pressure will be 110 stopped and vice versa; in order to keep the fixed position, a thumb nut 39 is screwed on top.

Variations may be resorted to within the scope of the invention, and portions of the 115 improvements may be used without others.

Having thus described my invention, I claim:

1. A demountable printing drum for a stenciling machine, having a part of its surface perforated like a sieve and forming a closed cylinder for taking a stock of ink inside, eliminating internal ink trough and distributing means, said perforated surface being of smaller area than the stencil printing-surface, said perforated area being perforated less at its edges than at its center, said cylinder being so designed that the stock of ink will lie in an imperforated part of the drum when the machine is stopped and ink 120 125 130

being introduced through a hole in a drum-side-plate fitting to the ink-package.

2. A demountable printing drum for a stenciling machine, having an adjustable crank or crank-pin, moving by means of an adjustable actuating arm slotted swing-levers, putting in action an axle, moving a paper-feeder with automatic leg-switch and slotted inclined bearings, causing thus weight-stoppage of the rubber-roll, said adjustable crank, crank-pin, actuating-arm altering the beginning of paperfeeding, said leg-switch raising the paper-feeder from the table as soon as the last sheet of paper is consumed, said feeder-rubber-roll being with its axle in inclined slotted bearings pressing when moving forward against an adjustable brake.
